(57) **CLAIM**

The ornamental design for an athletic shoe sole with air chambers as shown and described.

DESCRIPTION

FIG. 1 illustrates an isometric top frontal view of a sole.

FIG. 2 illustrates an isometric top rear view thereof.

FIG. 3 illustrates a frontal orthogonal thereof.

FIG. 4 illustrates a rear orthogonal view thereof.

FIG. 5 illustrates a left-side orthogonal view thereof.

FIG. 6 illustrates a right-side orthogonal view thereof.

FIG. 7 illustrates a top orthogonal view thereof; and,

FIG. 8 illustrates a bottom orthogonal view thereof.

1 Claim, 4 Drawing Sheets
